NEWMAN H. HOLLAND, OF WEST ORANGE, NEW JERSEY, ASSIGNOR TO NEW JERSEY PATENT COMPANY, OF WEST ORANGE, NEW JERSEY, A CORPORATION OF NEW JERSEY.

SPEAKING-TUBE SUPPORT FOR PHONOGRAPHS.

1,297,466.

Specification of Letters Patent. Patented Mar. 18, 1919.

Application filed July 13, 1914. Serial No. 850,804.

To all whom it may concern:

Be it known that I, NEWMAN H. HOLLAND, a subject of the King of Great Britain, and a resident of West Orange, Essex county, 5 New Jersey, have invented a new and useful Improvement in Speaking-Tube Supports for Phonographs, of which the following is a description.

This invention relates to a support for 10 speaking tubes of phonographs and particularly of those of the business or commercial type. The speaking tubes now in common use comprise a mouth-piece connected to the phonographic recorder by a convenient 15 length of rubber tubing or the like. This tubing is liable to be in the way of the operator or be injured when not in use. To overcome this inconvenience and difficulty, I provide at a convenient point a bracket-like member, 20 one of the functions of which is to act as a support for the speaking tube when the latter is not in actual use, but which is also constructed to serve as a means for operating the switch or other member which 25 controls the starting and stopping of the driving mechanism or other movable parts of the phonograph.

In the accompanying drawing which forms a part of this specification:

30 Figure 1 represents a perspective view of part of the phonograph containing one embodiment of my invention;

Fig. 2 is a view of the same partly in vertical section and partly in side elevation;

35 Fig. 3 is a section on line 3—3 of Fig. 2;

Fig. 4 is an enlarged perspective view of one form of the bracket forming a part of my invention; and

40 Figs. 5 and 6 show in perspective modifications in the details of construction of the bracket.

Like characters are employed to designate similar parts throughout.

Referring to the drawing the numeral 1 45 indicates the casing containing the motor and other operating parts of a phonograph, the casing being provided with a frame or support 2 on which is mounted the shaft of the pulley 3 which, as is common in the art, 50 is driven from the phonograph motor or driving means, and imparts rotation to the mandrel 4 carrying the record 5. Fastened to the top of the casing 1, as by two screws, 6 and 6', is a metallic plate 7 provided with

a lug or bracket 8 projecting upwardly at 55 right angles from the plate 7, the said bracket having a hinge loop 9. The plate 7 has a central hole 10 of suitable dimensions for receiving the top of the stop and start button 11 of the switch 12 located with- 60 in the casing. The hinge loop of the bracket carries a wire bracket 13 projecting outwardly and terminating in a hook or loop 14 arranged in front of the casing and serving as a rest for the speaking tube 15. The 65 bracket 13, as shown, has parallel arms 16 and 16'. A slide 17, having an upwardly extending lug 18 and a groove 19, is mounted on the two arms of the bracket, the groove 19 being adapted to engage, in a manner 70 shown in Figs. 2 and 3, the head of the button 11 of the switch controlling the driving means.

Referring to Fig. 2, the working of the device will be apparent. In the modification there shown, the wire bracket 13 is lifted manually to the position indicated by dot and dash lines when it is desired to start the motor, whereby the button 11 of the switch, being engaged by the slide 17, is 75 raised and the switch moved to starting position. When the operator places the speaking tube in the bracket 13, as shown in full lines in Figs. 1 and 2, the speaking tube, by reason of its weight, causes the bracket 13 80 and the button 11 of the switch to be pressed downwardly to stop the motor. The dot and dash lines in Fig. 2 show the elevated position of the bracket 13 and the button 11 prior to the placing of the speaking tube 85 in the bracket. By moving the slide 17 along the arms 16 and 16', the said slide may readily be engaged with or disengaged from the button 11. The dotted lines in Fig. 2 90 show the bracket in inoperative position with the slide 17 disengaged from the button 11. It will be seen that with the bracket 13 in this position, the button 11 may be readily operated directly by hand.

Figs. 5 and 6 show two modifications of 100 the device, which tend to increase its usefulness. The modification shown in Fig. 5 consists in mounting on the downwardly extending part of the loop 14 of bracket arm 13 a support 20 having a curved inwardly 105 extending spring tongue 21, this spring tongue offering a sufficient amount of resistance to the removal of the speaking tube

deposited in the loop 14 as to raise the bracket 13 and the button 11 controlling the switch when the speaking tube is thus removed. The same object is attained in a 5 slightly different manner in the modification shown in Fig. 6. By extending the point of the loop 14 inwardly in the manner there shown, use is made of the tendency of the operator to pull the tube toward himself 10 to the position shown in dotted lines in Fig. 6 when removing the tube from the loop. It is evident that the tube in its movement will strike against the inward bend of the loop, and the involuntary upward movement following 15 the interference by said bend will be sufficient to raise the bracket member 13 and with it the button 11 engaged by the slide 17. The replacement of the tube to the loop 14 will again effectuate the stopping of 20 the motor as before.

From the above description, it will be seen that my new device efficiently and advantageously combines the several functions of a support or rest for a speaking tube with 25 means for automatically controlling the starting and stopping mechanism of the phonograph in a manner best adapted to the customary way of using such apparatus. I wish it distinctly understood that this description comprises but some embodiments 30 of my invention, and I may modify the same in many different ways without departing from the spirit of my invention.

Having now described my invention, what 35 I claim as new and desire to protect by Letters Patent is as follows:

1. In a phonograph, driving mechanism, including means for controlling the operation of the same, a movable support for a 40 speaking tube and means engaging said controlling means and support whereby said controlling means may be actuated by said support, said engaging means being movable out of engagement with said controlling means, substantially as described.

2. The combination of movable phonographic mechanism, driving mechanism therefor including means for controlling the operation of said driving mechanism, and 50 a movable support for a speaking tube connected with said controlling means, said support being provided with means for automatically causing the support to operate said controlling means on the removal of the 55 speaking tube from said support, substantially as described.

3. In a phonograph, driving mechanism including means for controlling the operation of the same, a movable support for a speaking tube, and a slide mounted on said sup-

port and adapted to engage said controlling means, substantially as described.

4. In a phonograph, driving mechanism including means for controlling the operation of the same, a movable support for a speaking tube connected to said controlling means, and a spring mounted on said support for resisting the removal of the speaking tube from said support, substantially as described. 70

5. In a phonograph, the combination with driving mechanism including means for controlling the operation thereof, of a movable support for a speaking tube, and a slide mounted upon said support and having a 75 groove adapted to engage said controlling means, substantially as described.

6. In a phonograph, movable phonographic mechanism, driving mechanism therefor including means for controlling the 80 operation of the said driving mechanism, and a movable support for a speaking tube or the like connected to the controlling means and arranged to operate said controlling means, substantially as described.

7. In a phonograph, movable phonographic mechanism, driving mechanism therefor including means for controlling the operation of said driving mechanism, a movable support comprising spaced arms upon opposite sides of said controlling means, and a slide mounted upon said arms and normally engaging said controlling means, substantially as described.

8. In a phonograph, a casing, movable phonographic mechanism, driving mechanism therefor including means for controlling the operation of said driving mechanism, and a movable support for a speaking tube or the like mounted outside of the casing, normally connected to said controlling means, and arranged to operate the controlling means, substantially as described.

9. In a phonograph, a casing, movable phonographic mechanism, driving mechanism therefor including means for controlling the operation of the same, a movable support for a speaking tube or the like mounted outside of the casing and comprising spaced arms upon opposite sides of said controlling means, and a slide mounted upon said arms and normally connected to said controlling means, substantially as described.

This specification signed and witnessed this 10th day of July, 1914.

NEWMAN H. HOLLAND.
